CLAIM

The ornamental design for a rotary card box, as shown and described.

DESCRIPTION

FIG. 1 is a perspective view of a rotary card box design showing my new design.

FIG. 2 is a front view of a rotary card box.

FIG. 3 is a rear view of a rotary card box.

FIG. 4 is a left side view of a rotary card box.

FIG. 5 is a right side view of a rotary card box.

FIG. 6 is a top view of a rotary card box.

FIG. 7 is a bottom view of a rotary card box; and,

FIG. 8 is a perspective view thereof, showing the rotary card box in an open state of use.

The portions of the drawings shown in broken lines represent stitching, which does form part of the claimed design.
